UNITED STATES PATENT OFFICE.

FREDERICK SEARLE, OF WORCESTER, MASSACHUSETTS, ASSIGNOR TO
LORING COES & COMPANY, INCORPORATED, OF WORCESTER, MASSACHUSETTS, A CORPORATION OF MASSACHUSETTS.

CONSTRUCTION OF WRENCHES.

SPECIFICATION forming part of Letters Patent No. 699,719, dated May 13, 1902.

Application filed February 3, 1902. Serial No. 92,288. (No model.)

To all whom it may concern:

Be it known that I, FREDERICK SEARLE, a citizen of the United States, residing at Worcester, in the county of Worcester and 5 State of Massachusetts, have invented a new and useful Improvement in the Construction of Wrenches, of which the following, together with the accompanying drawings, is a specification sufficiently full, clear, and exact to 10 enable persons skilled in the art to which this invention appertains to make and use the same.

My present invention relates to an improvement in the means for combining and securing 15 the jaw-adjusting screw in connection with the collar or end of the handle-frame, bar, and bar-shank, the objects being to render the structure more desirable and to provide a strong, neat, and efficient interlocking 20 attachment that can be manufactured and assembled with practical facility. I attain these objects by the construction illustrated in the accompanying drawings, wherein—

Figure 1 represents a side view of a wrench 25 embodying my invention, a portion being drawn in section to show the improved construction. Fig. 2 is a transverse section of the bar and screw-journal at the end of the handle at line W W, Fig. 1. Fig. 3 is a trans- 30 verse section of the handle-frame at line XX on Figs. 1 and 4. Fig. 4 is a longitudinal central section of the upper portion of the handle-frame at line Y Y on Fig. 2. Fig. 5 is a cross-section of the bearing or step at line 35 Z Z on Fig. 2. Fig. 6 is a perspective view of the key-piece. Figs. 7, 8, and 9, respectively, show an end, top, and longitudinal section of the key-piece. Figs. 10, 11, and 12 show top and section views of the key-piece as 40 made in two parts.

Referring to the drawings, A denotes the wrench-bar, having a fixed jaw a and handle-supporting shank. B indicates the movable jaw that slides on said bar, C the jaw-adjusting screw having the rosette thereon, the axis 45 of the adjusting-screw being disposed so that said rosette C' stands clear of the front face of the bar, which is unnotched at the back of the rosette, and D indicates the handle-frame, which parts are of previously-known

construction, excepting in the particulars hereinafter specified.

The screw-journal is made in T shape or with a groove 2 and flange 3. (See Fig. 1.)

In accordance with my present improvement I form in the top end of the handle frame or collar a T-shaped or undercut open cavity 5, extending forward from the bar-opening 6 to the position of the screw-bearing and having a circular end concentric 60 with the screw-axis and corresponding to the form of the screw-journal. The width of the upper part of said cavity corresponds with the diameter of the grooved portion 2 of the screw-journal, and the lower part of said 65 cavity corresponds with the diameter of the flange portion of said screw-journal. Said T-shaped cavity can be formed or dressed out by means of a suitably-shaped milling-cutter inserted at the bar-opening 6 and 70 worked horizontally toward the position of the screw-bearing axis, forming an integral inwardly-overhanging lip 9. The cavity and screw-journal can be formed with square lips and shoulders, as indicated in Fig. 5, or with 75 lips of other suitable form, as rounded lips and shoulders, as indicated by the outline m adjacent to Fig. 5.

Corresponding with the cavity 5 I provide a key-piece 10, of inverted-T cross-section 80 (see Figs. 6, 7, 8, and 9) and having one end 11 formed to seat against the neck a' of the bar-shank adjacent to the handle-positioning shoulder 8, while its other end 12 is laterally concaved on two different circles, as at 13 and 85 14, to countermatch the periphery of the grooved and flanged portions of the screw-journal. The sides 15 of the key-piece 10 are formed to countermatch and interlock with the undercut sides of the cavity, so that said 90 key-piece can be slipped endwise into the cavity from the bar-opening 6 and to fill the cavity, with the exception of the journal-bearing space.

When assembling the parts, the jaw B is 95 first threaded onto the end of the screw, and the screw-journal is entered at the bar-opening (see dotted lines on Fig. 4) and is then passed laterally into its bearing-seat at the outer end of the cavity by movement in the direction 100

indicated by the arrow, the flanged portion 3 of the journal engaging beneath the inwardly-projecting lip 9 of the bearing. The key-piece 10 is then inserted in the cavity, following the screw-journal, its upper part 13 overlying the flange 3, said upper part and the lip 9 confining the screw with sufficient looseness to permit free rotation of the screw, but interlocking the screw against endwise movement. The bar A is then passed through the jaw B and inserted in the handle-frame, the neck of the bar-shank filling the opening 6 and the end of the collar and top corner of the key-piece 10 resting against the shoulder 8, the handle-frame being then secured to the bar-shank in any suitable manner.

In some instances, if desired, the key-piece may be made in two parts, the upper and lower sections being separate, as illustrated in Figs. 10, 11, and 12. In such instances the upper portion of the key-piece and cavity may be slightly dovetailed to give the upper section better retention, although said section would be retained by the shoulder 8 and rosette end.

What I claim as of my invention, and desire to secure by Letters Patent, is—

1. In a wrench, a wrench-handle collar provided with a screw-bearing seat having an integral inwardly-overhanging lip, a jaw-adjusting screw having a flanged journal laterally interlocking beneath said lip, a counter-matching key-piece embracing the journal opposite said lip, and means securing said key-piece in position, for the purpose set forth.
2. In a wrench, the handle-collar having an undercut screw-bearing seat with an open undercut cavity extending to the bar-space or collar-opening, into which the flanged screw-

journal is interlocked by insertion at the collar-opening and transverse passage to its seat; and an interlocking follower or key-piece fitting said cavity and confining the screw-journal in its bearing, substantially as set forth.

3. The combination, of a wrench-handle frame provided in its collar end with an undercut cavity extending to the screw-axis, and having an inwardly-overhanging lip and round end seat for receiving the journal; the jaw-adjusting screw having a T-shaped journal, and the insertible key-piece block provided with side lips adapted for engaging beneath said overhanging lip on the handle-frame, and a transversely-concaved end with a lip countermatching the screw-journal, and a rear end matching the face of the wrench-bar neck.

4. In a screw-wrench comprising a wrench-bar having a straight body, a fixed jaw and a handle-supporting shank with front and rear collar-positioning shoulders, and a movable jaw slideable on said bar; the jaw-adjusting screw having a rosette and a grooved and flanged step-journal, a handle-frame fitting upon said bar-shank against said shoulders, and having an inwardly-lipped bearing-seat for said screw-journal with an open channel having undercut sides extending thereto from the collar-opening, and a key piece, or pieces, fitting in said channel with the end thereof confined beneath the collar-positioning shoulder and against the neck of the bar-shank.

Witness my hand this 30th day of January, 1902.

FREDERICK SEARLE.
